UNITED STATES PATENT OFFICE.

WILLIAM CLIFFORD, OF DULUTH, MINNESOTA.

DREDGE CONSTRUCTION.

Application filed August 24, 1925. Serial No. 51,961.

To all whom it may concern:

Be it known that I, WILLIAM CLIFFORD, a citizen of the United States, residing at Duluth, in the county of St. Louis and State 5 of Minnesota, have invented certain new and useful Improvements in Dredge Constructions, of which the following is a specification, reference being had therein to the accompanying drawing.

10 This invention relates to a novel method of transforming a common freight vessel into a dredge, and has special reference to such a method particularly adapted to the simple and economical converting of what is 15 known as the Fredrickstad type of transports built during the war and now of questionable service to a form of vessel or hydraulic dredge for which there is great demand.

20 The objects being obvious I will now proceed to describe the steps of the method as depicted in the accompanying drawings forming part of this application and in which like reference characters indicate like 25 parts.

Figure 1 is a side elevation of the common type of transport used during the World War period and known as the Fredrickstad type of ship.

30 Figure 2 is a partial cross-section of same.

Figure 3 is a similar view to Figure 1 showing the relative position of the deck and cabins to the hull after conversion; and

35 Figure 4 is a similar view to Figure 2 after conversion.

The number of this type of transport vessel now of comparatively little value is well known to those versed in the art as is also the demand for the resultant product in the 40 form of an hydraulic dredge, and the first step in the act of conversion resides in cutting off the forward and after ends of the vessel on approximately the lines 1—1 and 2—2 respectively, and scrapping same, thus 45 leaving the pilot house 3, midship superstructure 4, boilers 5, and engine 6 intact in the centermost section of the vessel.

This being accomplished results in the 50 remaining section being rather top heavy in proportion to its horizontal dimensions to overcome which the section is cut horizontally as indicated on the line 7—7 in Figure

2 and again on the line 8—8 Figure 2; the intervening portion being scrapped and the superstructure lowered so that it may be 55 reunited to the substructure, resulting in a vessel now of better proportions for the work intended, and, as is obvious, the vertical section removed may be any desired depth, but in practice from six to eight feet has proven 60 best.

Further slight modifications may be accomplished as for example the removal of the pilot house 3 to the opposite end of the superstructure, the cabin 4 continued as at 65 9, and the adding of a scow like bow and stern thereto; the nomenclature of the ends of the vessel being reversed as the bow of the dredge now becomes what was the stern or after part of the freight vessel. 70

The shaft of the vessel being cut is suitably connected or geared as desired to the pump 10, the suction of which is illustrated at 11 and depends from the bow of the dredge as at 12, the mast and boom for supporting and controlling same being illustrated at 13 and 14 respectively, while at the opposite end of the dredge or stern is mounted in any desired manner the anchoring 75 spuds 15. 80

In this manner there is provided a simple and inexpensive method of producing an exceedingly practical and efficient dredge; this particular type of freight vessel being had at low cost and the transformation requiring 85 much less expenditure than the cost of new machinery and equipment as found within such vessels.

Having thus described my invention, what I claim and desire to secure by Letters Patent, is:

The herein described method of transforming a common freight vessel into a hydraulic dredge comprising first removing the 95 ends of the vessel and forming a scow like bow and stern to the midship section, removing a vertical section of the sides of the hull and reuniting the remaining portions, and connecting hydraulic dredge machinery to the power unit as found in the vessel. 100

In testimony whereof I hereunto affix my signature.

WILLIAM CLIFFORD.
